CLAIM

The ornamental design for a collectible coin holder, as shown and described.

DESCRIPTION

FIG. 1 is a perspective view of a collectible coin holder showing our new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a cross-sectional view taken along line 8-8 in FIG. 2.

FIG. 9 is an exploded perspective view thereof.

FIG. 10 is another perspective view thereof, shown in a used condition enclosed in an outer transparent case with a certification label shown in broken lines.

FIG. 11 is an exploded perspective view thereof, shown in a used condition with the front and back parts of the outer transparent case shown in broken lines.

FIG. 12 is a perspective view of the interior side of a front panel of FIG. 1, shown separately for ease of illustration.

FIG. 13 is a front elevation view of FIG. 12; and,

FIG. 14 is a back elevation view of the interior side of a back panel of FIG. 1, shown separately for ease of illustration. The dot-dashed broken lines shown in FIGS. 9 and 12-14 illustrate boundary lines and form no part of the claimed design. The even dashed broken lines shown in the drawings represent portions of the collectible coin holder that form no part of the claimed design.
